UNITED STATES PATENT OFFICE

2,189,385

FLOOR RACK FOR REFRIGERATOR CARS

Vinton E. Sisson, Winnetka, Ill., assignor, by
mesne assignments, to Standard Railway
Equipment Manufacturing Company, Chicago,
Ill., a corporation of Delaware

Application August 17, 1938, Serial No. 225,275,
now Patent No. 2,147,130, dated February 14,
1939, which is a division of application Serial
No. 167,771, October 7, 1937, now Patent No.
2,147,129, dated February 14, 1939. Divided
and this application November 7, 1938, Serial
No. 239,314

2 Claims. (Cl. 62—19)

The invention relates to insulated railway refrigeration cars used to transport perishable commodities, such as vegetables, fruits, berries, meats, eggs, frozen fish, etc., and to maintain such commodities while in transit at a predetermined range of temperature, thus necessitating the use of a cooling means in the summer and a heating means in the winter. It has been found that perishable commodities which

10 have not been allowed to get too cold (freeze) or too hot (bake) have a high market value because they have a longer storage life.

In a refrigerator car water ice is associated with certain elements of the car to establish a 15 conventional circulation of air between the refrigeration chamber and the lading compartment to cool the lading in the car (as hereinafter described). A foraminous floor supports the lading in spaced relation to the insulated floor of the car.

It is desirable to allow at least some of the melted ice to remain on the insulated floor of the car below the foraminous floor to produce further insulation between the outside of the car 25 and the air flues below the foraminous floor and also to further cool the circulating air. The melted ice (water) has a temperature of about 32° Fahrenheit when no salt is used and as low as 14° Fahrenheit when 25% salt is mixed with the lump ice, therefore, it can effectively perform 30 the two above mentioned functions. The service movements of the car, that is, the stopping and starting, as well as the swaying movement, cause the melted ice to be thrown against the foraminous floor supports, bulkhead supports, threshold and other projections and splash through the 35 openings in the foraminous floor and against the lading. In package lading the containers would be soiled and in loose lading such dampness 40 might cause the commodity to rot.

An object of the invention is to position the refrigerant ice so that the melted ice (water) will drain upon the insulated floor below the foraminous floor and to construct the foraminous 45 floor so that the melted ice (water) will not splash through the foraminous floor.

In the drawing:

Figs. 1 and 2 show the relation of my improved floor rack to the other elements of a 50 refrigerator car to guide the circulating air from the refrigeration chamber to the lading compartment for cooling a lading as hereinafter described.

Fig. 3 shows the means associated with the 55 stringers to cover the spaces between adjacent

slats adjacent the stringers to prevent splashing of melted ice through the foraminous floor.

In the form of my invention illustrated the refrigerator car is provided with a bulkhead 2 separating the refrigeration chamber 3 from the 5 lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the ice supporting means 12 in the refrigeration chamber 3 in spaced relation to the floor 6 of the car and the basket (or netting) 13 spaces the refrigerant from the end wall 14 and bulkhead 2 to provide the flues 16—17. The apertured floor rack, or 15 foraminous floor, supports the lading so as to provide the space 20 which communicates with the flues 16—17. A refrigerant, such as ice in the refrigeration chamber, induces a convection circulation of air from the flues 16—17, through 20 the flue space 20 and the apertures 21 in the floor rack, and as the air is warmed by the lading, it rises and passes through the bulkhead upper opening 7 and thence through the flues 16—17, and being cooled by the refrigerant, repeats 25 the convection cycle.

When a stove or other heater is placed in the refrigeration chamber a convection circulation of air is induced in the opposite direction because 30 the air warmed by the heater rises and falls when cooled by the lading.

In the form of my invention shown in Fig. 3 the foraminous floor 18 comprises a plurality of spaced apart slats 25 supported by stringers 26 upon the insulated floor 6 of the car, which 35 stringers are preferably positioned parallel to the direction of movement of the circulating air and the spaced apart slats 25 extend normally to the stringers 26. The refrigerating circulating air passes through the spaces 27 between the 40 slats. Screws, bolts, nails or any other securing means may be used. Short members 40 are secured to the stringer 26 in the spaces 27 between adjacent slats 25 which extend beyond both sides of the stringer to stop the splashing water. The 45 upper surfaces 41 of these members are preferably sloped to provide a water-shed.

The accompanying drawing illustrates the preferred form of the invention, though it is to be understood that the invention is not limited to 50 the exact details of construction shown and described, as it is obvious that various modifications thereof, within the scope of the claims, will occur to persons skilled in the art.

This is a division of my co-pending applica- 55

tion No. 225,275, filed August 17, 1938, now matured into Patent No. 2,147,130, which is a division of my co-pending application No. 167,771, filed October 7, 1937, now matured into Patent No. 2,147,129.

I claim:

1. In a refrigerator car having an insulated floor, a foraminous floor above the insulated floor, and a space between said floors, the refrigerating ice which induces an air current in said space being positioned so that the melted ice will drain upon said insulated floor, said foraminous floor comprising a plurality of spaced

apart parallel slats, a stringer extending normally to and supporting said slats upon the insulated floor, and members secured to the stringer in the spaces between the slats which extend beyond the sides of the stringer whereby said members prevent the melted ice from splashing against the stringer and resplashing through the spaces between the slats.

2. A structure as defined in claim 1 wherein the upper surfaces of said members are sloped to provide water sheds.

VINTON E. SISSON.
